UNITED STATES PATENT OFFICE

THOMAS J. OSINGA, OF CHICAGO, ILLINOIS

ELEVATOR DOOR CONTROL

Application filed December 5, 1927. Serial No. 237,889.

This invention relates to elevators of the type used in office buildings, factories and the like and more particularly to the means for opening and closing the doors of the same, and it is my main object to provide a mechanism for this purpose which is simple and efficient.

A further object of the invention is to construct the novel appliance to operate automatically whereby to open the door of the elevator as the latter stops at a given floor, and to close the same as the elevator resumes its course.

A still further object of the invention is to construct the novel mechanism in such a manner that it will not require adjustments or frequent attention.

Another object of the invention is to provide a means whereby the usual pneumatic and hydraulic check incident to each floor is eliminated.

A final, but nevertheless important object of the invention is to incorporate the safety switch commonly called the interlock in the structure of the car, thereby eliminating the need of such a switch on each floor.

With the above objects in view and any others that may suggest themselves in the specification and claims to follow, a better understanding of the invention may be gained by reference to the accompanying drawings, in which—

Figure 1 is an elevation of so much of the elevator shaft as involves one door installation, such door and associate parts being shown;

Fig. 2 is a side elevation of the lower and frontal part of the car, in connection with a cooperating element in the shaft;

Fig. 3 is an enlarged vertical section of the medial portion of a cross head shown in Figure 2;

Fig. 4 is a detail section on the line 4—4 of Figure 2;

Fig. 5 is a similar section on the line 5—5 of Figure 2;

Fig. 6 is a diagrammatical view of the electrical circuit involved in the control mechanism;

Fig. 7 is a view similar to Figure 2 show-

ing a modification for the manual operation of the control; and

Fig. 8 is a section on the line 8—8 of Figure 7.

In the operation of an automatic elevator door control, the operation of the door is usually induced by a switch arrangement on the elevator operator's hand lever. I employ the same expedient in my case, in accordance with the diagrammatic showing in Figure 6, in which the operator's lever is denoted by 10 and the auxiliary switch contacts by "A," "B," and "C." Thus, the lever is intended to bridge the contacts "A" to complete the circuit in a forward lead 11, and contacts "B" or "C" to complete the circuit in a reverse lead 12, the leads 11 or 12 cooperating with the negative or return lead 13 of the circuit. The theory of the circuit while the lever is in upright position is to secure the opening of the door, since the upright position of the lever indicates that the car has come to a stop. On the other hand, when the lever is moved in either direction from the center, the car is set in motion and the door must therefore be closed. Hence, the provision of the switch contacts "B" and "C," which control the same lead selectively, depending on whether the car rises or falls from the stationary position.

My intention is that the bringing of the hand lever 10 to the medial or "stop" position shall induce the operation of a motor 14 in a given direction, which according to Figure 2 induces the upward travel of a gear rack 15 in mesh with a pinion 16 on the motor shaft. The gear rack 15 carries a slide 17, suitably guided between rollers 18 and 18a; and the slide has a gradually-inclined cam bar 19 which becomes effective upon the roller 18a to urge the same away from the slide 17. While the motor and roller 18 are carried by the car 20, the roller 18a is carried upon one end of a horizontal bar 21 of angular cross section, as noted in Figure 5, such bar being journaled to slide in standards 22 mounted on an angle shelf 23 carried by the side wall of the car 20. The slide bar 21 carries at its opposite end a cross head 24, which extends in a vertical

direction and terminates in upper and lower receding sections 24a. The cross head also carries a rubber or other non-metallic buffer 25, suitably encased in a socket 26 and cushioned by springs 27 suitably installed in the cross head.

The general action of the slide bar 21 is to advance the cross head 24 toward the left, as viewed in Figure 2, and this action is in 10 connection with a linkage which operates the door 28. As more clearly noted in Figure 1, the door 28, equipped with the usual overhead slide bearings 29, receives its motion by the action of links 30 and 31 which 15 break in an upward direction on a medial pivot pin 32 when they are to open the door, the link 30 being pivotally attached to the door frame at its outer end as indicated at 33, and the link 31 being similarly attached 20 to the door as indicated at 34. For my purpose, the links are operated through the agency of a pusher 35, effective upon an off-set 30a of the link 30 by a pivotal connection 36. Thus, the off-set motion of the 25 pusher 35 for a short distance operates the links to a sufficient extent to draw the door fully open; yet, the travel of the pusher 35 is limited owing to the leverage in its relation to the link 30. The return of the 30 link 30 is effected by a coil spring 37, passing from the off-set 30a to a pin 38 projected from the door frame; and the travel of the pusher 35 is guided by the application of a roller 39 carried by the lower end of the 35 pusher along the upright 40 of the door frame adjacent to the parts now being described. The pusher is extended downwardly with a pair of break links 41 and 42, clearly shown in Figure 2, which are intended to act as a lever when actuated in a straightening direction to lift the pusher and 40 accomplishes the opening of the door as described.

The joint of the links 41 and 42 is preferably made with a roller 43 upon which the straightening stress is exerted by the pressure of the cross head 24 through its buffer 25 as the cross head is moved in an advancing direction, such as when the roller 50 18a at the rear end of the slide bar 21 is crowded by the cam incline 19.

It will now be seen that as the motor 14 continues to operate, the cross head 24 will be urged toward the left whereby to occasion 55 the opening of the door as described. The rack bar slide 17 carries an enlargement 44 which at this time impinges upon a spring button 45 in the motor circuit whereby to break the same and shut off the motor, so 60 that while the car is stationary the motor has only operated as long as it was necessary to effect the opening of the door and was cut off as soon as the door had opened to its full extent. The parts involved 65 remain stationary until the car is again

started, in which event the drawing of the operator's hand lever to close the switch contacts "B" or "C" turns in the reverse lead 12 causing the motor 14 to assume motion in a reverse direction. This motion, of course, 70 draws the rack bar 15 down again and releases the slide bar 21 so that an expanding spring 46 around the same may urge it through the agency of a fixed collar 21a to assume a return motion and therefore withdraw the cross head 24 from its pressure upon the roller 43. At this juncture, the spring 37 of the door frame exerts its tension to close the door. Also, the enlargement 44 on the rack bar slide 17 has descended 75 to operate a button 47 having the same effect as the button 45 but on the reverse lead 12 whereby to disconnect the motor 14 when the door has already closed. Thus, the motor 14 is only in operation when the 80 door is performing its opening or closing movements.

It is now evident that the cross head 24 is carried during the travel of the car along a vertical path represented by the position 90 of the cross head of Figure 2, from which it is apparent that the buffer 25 passes the roller 43 corresponding to each floor in slightly spaced relation when the respective 95 doors are allowed to remain closed. Thus, the cross head is generally operated only when a desired door is to be opened. However, there are periods in the running of elevators when the operator slows down or stops the car at an intermediate point 100 between floors. In such an event, the structure described would cause the cross head to be projected to the limit of its travel, placing the same in the way of any given roller 43 in case the car should suddenly rise or 105 fall in proximity to a floor. It is therefore my intention to include in the mechanism a means which will only permit the cross head to project to its limit when the same is opposite a floor, so that the stopping of 110 a car between floors will not impart a working stroke to the cross head.

In order to attain the last mentioned result, I bring the motor circuit to the site of the cross head in the form of a contact gap 48, more clearly shown in Figure 3. Opposite the gap the buffer 25 is fitted with a bridging plate 49, which closes the gap when the buffer recedes into the cross head along its cushioned supports 27. Also, I provide on top of the shelf 23 a cut-out switch box 50, having a lever 51 operated by the slide bar 21 whereby to effect the cut-out as the slide bar moves in a forward direction a short distance, that is, a partial effect of the cam incline 19 upon the roller 18a of the slide bar. Assuming that the forward motion of the slide bar 21 is occasioned by the stopping of the car, as explained before, the presence of a floor as represent- 115 120 125 130

ed by the roller 43 will, through the initial motion mentioned, cause the cross head 24 to impinge upon said roller with its buffer 25 whereby to close the circuit gap 48. Thus, although the switch lever 51 initially effected the cut-off of the current for the motor, the presence of the roller 43 and therefore of a floor opposite the car has immediately caused a resumption in the operation of the motor, so that the door will be opened as previously explained. However, should the car cease its travel at a point between floors the absence of the roller 43 will cause the buffer 25 and the cross head to remain electrically disconnected, so that the initial breaking of the circuit by the cut-out switch lever 51 will cause the motor to stop at an early stage whereby to maintain the cross head in but slightly advanced position. This position will occasion no harm, since the spring 46 on the cross bar 21 may return the cross head to initial position. Or, in sweeping up or down past the roller 43 incident to the floors, the buffer 25 may be caused by such roller to recede to a position corresponding to the initial position of the cross head. The slanting ends 24a of the cross head are, of course, provided to place the same in a receptive position as against the rollers 43 to effect a recession of the slide bar 21 automatically in case the cross head has in some manner exceeded its predetermined inactive advance. Alongside the switch box 50 may be positioned a similar box 50a, indicated in Figure 5, with a suitable operating lever 51a, to cut off the power of the car at the same time that a door is to be opened. It will be understood, of course, that the levers 51 and 50a will merely be tripped into the cut-out box on the forward stroke of the slide bar 21, and in turn be swung back into closed position of the return stroke of the slide bar. In the diagrammatic representation of Figure 6, but a suggestion of the car power circuit has been shown in the form of the cut-out switch 50a. A dual installation of the circuit gap 48, in parallel has been shown, to assure contact in case the cross head is unevenly urged. Where an electrical motive installation is not desired for the control of the elevator doors, I have modified my original construction to make the control hand operated. Thus, in Figures 6, 7 and 8, 52 represents the operator's hand lever. The lever is shown in inactive position of the car, and it may be swung on the pivot 54 toward the right when the car has been stopped at a given floor and the door is to be opened. As noted, a simple slide bar 55 and cross head 56 construction has been shown in connection with the roller 43 and other parts incident to the door operating mechanism, but instead of a power drive for the slide bar 55, the lower part of the lever 52 is used as a pusher

against an arm 57 mounted on the slide bar 55 to project the cross head to the extent of operating the door mechanism. This action is of a simple character, but for the return of the cross head, it will be recalled that in the electrical case, the motion of the door was controlled by the cam incline 19 so that the opening and closing could start and end gradually, through the flattening of the cam incline contour at the ends as shown, eliminating the need of the customary pneumatic or hydraulic check for these purposes; in the present or manual case, however, I add the expedient of standard air check 58 to induce return of the slide bar 55 in the same manner as an ordinary door. A suitable lever arrangement 59 is provided between the slide bar and the cylinder plunger 60. Thus, when the slide bar 55 is actuated in a forward direction, no resistance is offered to the plunger 60, and the door is therefore caused to open quickly; however, on the return pull of the air check, the checking action in the cylinder comes into play near the end of the stroke, permitting the door to close gradually.

For the proper operation of the modified controls, I use the lower end of the arm 57 as a cam to force an elevator-power switch lever 61 over toward the left (Fig. 7) on the advance of the slide bar 55. The swing of the lever 61 is by spring tension, the current being cut off as soon as the lever 61 swings away. The arm 57 then rides over the lever as the door is caused to open and close, again making contact when the door has fully receded, to close the circuit for the car-operating lever and enable the car to leave the floor.

I deem it advisable to indicate in Figure 7 a latch 53 which may be used—after the hand lever 52 has been swung to the door opening position—in cooperation with a notch 53a in the guide sector, to lock the lever in such position. This is an expedient to retain the door in open position while the operator momentarily leaves the car, so that the door may not be drawn closed by the air check and the operator locked out.

In the diagrammatic showing of Figure 6, a simple circuit for a forward-reverse motor control is illustrated, and with the parts shown in the positions corresponding to the above description, it is not deemed necessary to describe the wiring of the circuit in detail.

I have thus provided a mechanism which is simple, does not require adjustments and is positive in action. Also, no difficulty is had in installing or handling the mechanism, and the same may be produced and installed at a great saving over existing systems for the same purpose. The electrical portion of the arrangement involves but a simple circuit, which uses few parts and is therefore 130

capable of use for long periods without any attention whatever.

While I have described and illustrated the invention in the preferred forms, it will be evident that the same is capable of many minor changes and refinements, and it is my intention to claim such changes and refinements as coming within the spirit and scope of the appended claims.

10 I claim:—

1. A means for opening an elevator door comprising a set of links breakable to draw the door open, a pusher effective on one of the links, a guide for the pusher, and a set of break links at the base of the pusher and expansible to operate the latter.

2. An elevator door control comprising a pressure-actuated door-opener installed in proximity to the door, a pressure-imparting element carried by the car and operative upon said door-opener, and a cam to impart a predetermined movement to said element.

3. An elevator door control comprising a pressure-actuated door-opener installed in proximity to the door, a pressure-imparting element carried by the car and operative upon said door-opener, a cam to impart a predetermined movement to said element, and a motor to operate said cam controlled by the movements of the car control.

4. An elevator door control comprising a pressure-actuated door-opener installed in proximity to the door, a pressure-imparting element carried by the car and operative upon said door-opener, and a cam to impart a predetermined movement to said element, the characteristics of said cam being to render the terminal portions of such movement gradual.

40 5. An elevator door control comprising a pressure-actuated door-opener installed in proximity to the door, a pressure-imparting element carried by the car and operative upon said door-opener, a cam to impart a predetermined movement to said element, a motor to operate said cam, and means carried by the cam to stop the motor after said element has received its predetermined movement.

50 6. An elevator door control comprising a pressure-actuated door-opener installed in proximity to the door, a pressure-imparting element carried by the car and operative upon said door-opener, an actuator for said element energized by the operating control of the car, and a de-energizer for said actuator rendered effective when the element has made a partial movement.

60 7. An elevator door control comprising a pressure-actuated door-opener installed in proximity to the door, a pressure-imparting element carried by the car and operative upon said door-opener, an actuator for said element energized by the operating control of the car, a de-energizer for said actuator

rendered effective when the element has made a partial movement, and a re-energizer for said actuator rendered effective when the element engages said door-opener.

8. An elevator door control comprising a pressure-actuated door-opener installed in proximity to the door, a pressure-imparting element carried by the car and operative upon said door-opener, a motor for said element energized by the operating control of the car, a motor de-energizing switch actuated by said element at the end of a partial movement, and a normally open motor switch carried by the element and adapted to engage the door-opener during said movement and be closed to re-energize the motor.

9. A means for operating an elevator door comprising a set of links breakable to draw the door open, a spring to expand the links for the closing of the door, a pusher effective on one of the links, a guide for the pusher, a set of break links at the base of the pusher and expansible to operate the latter, a slide bar carried by the car, a cross head frontally of the slide bar and effective to expand said latter-mentioned break links when the slide bar is advanced, a cam operative to advance the slide bar, a spring to retract the latter when the cam is ineffective, and a motor to operate the cam.

10. A means for operating an elevator door comprising a set of links breakable to draw the door open, a spring to expand the links for the closing of the door, a pusher effective on one of the links, a guide for the pusher, a set of break links at the base of the pusher and expansible to operate the latter, a slide bar carried by the car, a cross head frontally of the slide bar and effective to expand said latter-mentioned break links when the slide bar is advanced, a cam operative to advance the slide bar, a spring to retract the latter when the cam is ineffective, a motor to operate the cam, and a resilient buffer forward of said cross head and adapted to close a circuit when the cross head engages said latter-mentioned break links.

In testimony whereof I affix my signature.
